DEFIBRILLATOR ELECTRODE

David P. Chuboff, Mount Prospect, Ill., assignor to Zenith
Radio Corporation, Chicago, Ill., a corporation of
Delaware

Filed Apr. 20, 1964, Ser. No. 79,593

Term of patent 14 years

(Cl. D83—12)

FIG. 1

FIG. 2

FIG. 3

FIG. 4

FIG. 5

FIGURE 1 is a side elevational view of the defibrillator electrode of the invention;

FIGURE 2 is a plan view thereof;

FIGURE 3 is a bottom plan view thereof;

FIGURE 4 is a rear view thereof; and

FIGURE 5 is a front view thereof.

I claim:

The ornamental design for a defibrillator electrode, substantially as shown.
